US0D1070353S

(12) **United States Design Patent** (10) **Patent No.:** **US D1,070,353 S**
(45) **Date of Patent:** **** Apr. 15, 2025**

(54) **REFILL HEAD FOR A TOOTHBRUSH**

(71) Applicant: **Colgate-Palmolive Company**, New York, NY (US)

(72) Inventors: **Eduardo Jimenez**, Manalapan, NJ (US); **Al Aquanza Sprosta**, Maplewood, NJ (US); **Xiangji Ding**, YangZhou (CN); **Yanmei Ji**, Jiangsu (CN)

(73) Assignee: **Colgate-Palmolive Company**, New York, NY (US)

(**) Term: **15 Years**

(21) Appl. No.: **29/853,740**

(22) Filed: **Sep. 19, 2022**

Related U.S. Application Data

(62) Division of application No. 29/744,982, filed on Aug. 3, 2020, now Pat. No. Des. 967,633.

(57) **CLAIM**

The ornamental design for a refill head for a toothbrush, as shown and described.

DESCRIPTION

FIG. 1 is a top, front and left side perspective view of a refill head for a toothbrush according to an embodiment of the new design;

FIG. 2 is a bottom, rear and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 5 Drawing Sheets
